ELECTRICAL PROTECTIVE SYSTEM

Hans Klemperer, Belmont, Mass., assignor to
 Raytheon Manufacturing Company, Newton,
 Mass., a corporation of Delaware

Application August 7, 1946, Serial No. 688,909

3 Claims. (Cl. 175—294)

1

This invention relates to protective electrical systems, and more particularly to those systems used in connection with tests to determine the life span of current-operated devices, such as electric discharge devices or the like.

It is the main object of the present invention to provide a system as above described having means for disconnecting the energizing circuit of said current-operated devices in the event of a short or overload condition.

Another object is to provide an electrical system having means for providing a predetermined waiting period after a short or overload occurs, during which time said energizing circuit is made inoperative, and on termination of said waiting period to again put said circuit in operation and thereafter provide a predetermined probationary period to determine whether the short or overload recurs.

Still further objects of the present invention will appear to those skilled in the art as the description progresses both by reference thereto and the attached drawing, in which:

Fig. 1 is a wiring diagram of one embodiment of the present invention; and

Figs. 2 and 3 are graphs showing the function of the various components of the device with reference to time.

Referring to Fig. 1, there is shown a test circuit comprising a source of alternating current 10 connected through a relay contact 33 to the primary 11 of a high voltage transformer 12. The relay contact 33 is controlled by a circuit breaker B having a winding 31 for actuating an armature 72, said winding being connected, at one end, to a bus 30, said bus, in turn, being connected to a source of alternating current. The other end of said winding 31 is connected through a relay contact 26 and conductor 32 to a grounded bus 22.

The relay contact 26 is controlled by a relay R—1, said relay having a winding 23 which, when energized, as will be presently explained, actuates an armature 25 to which said relay contact 26 and three others are attached. One end of said winding is connected, by a conductor 41, to a protective lamp 24, and from said lamp, by a conductor 42, to an adjustable arm 44 which is adapted to select a potential across a low resistance 21. By low resistance is meant a resistor of the order of 200 ohms. The other end of the winding 23 is connected, by a conductor 43, to the junction of one end of the resistor 21 and ground.

The secondary 13 of said transformer 12 is

2

connected, at one end 14 thereof, to a load 15, said load, in turn, being connected to the anode 16 of a discharge tube 17, in this particular embodiment, a gaseous-discharging device. The other end 18 of the secondary 13 is connected, by a conductor 20, to the grounded end of the resistor 21, the high end of said resistor being connected to the cathode 19 of the tube 17.

The circuit, as shown in the drawing, illustrates the position of the various components therein when the test circuit above described is functioning normally. Under normal conditions of operation of said test circuit, the current flowing through resistor 21 is a moderate amount and the voltage developed thereacross insignificant. However, if a short circuit or overload occurs in said test circuit, considerable current will be drawn by tube 17 and an appreciable voltage drop will be developed across the resistor 21.

A portion of the voltage so developed is selected by the adjustable arm 44 and applied to the winding 23 of relay R—1. The lamp 24 serves to protect the winding 23 against excessive excursions of current therethrough.

The application of the selected amount of voltage to the winding 23 of relay R—1 actuates the armature 25, causing the relay contact 26 to open and interrupt the current flowing in the winding 31 of breaker B. The interruption of current in said breaker B causes armature 72 to withdraw the relay contact 33 from its normal position and, in turn, interrupt the flow of current 10 in the primary 11 of transformer 12. The last-named interruption of current deenergizes the test circuit of tube 17 and operation ceases.

At the instant relay R—1 becomes energized, as above described, a number of operations occur substantially simultaneously.

When relay R—1 is energized, the consequent deenergization of breaker B, in addition to causing the armature 72 to withdraw the relay contact 33 from its normal position, also causes said armature to withdraw a relay contact 34 attached thereto from its normal closed position. The opening of said relay contact 34 causes the interruption of current in a counting circuit, including bus 30, relay contact 34, an electrically operated counter 35, a conductor 36, and grounded bus 22. The counter 35 may be of the type which, upon the interruption of current therethrough, trips a relay to actuate a counting mechanism. The counting circuit in this

particular embodiment is incorporated for statistical purposes.

In addition to actuating the counting mechanism just described, the relay R-1, when energized, moves a relay contact 27, normally open, into closed position. It will be recalled that the opening of the relay contact 26 causes the cessation of operation of the tube 17. As a result, current ceases to flow in winding 23 of relay R-1 which would, if not otherwise provided for, result in said relay causing its attendant switches to assume their normal positions. However, because of the novel circuit arrangement of the present invention, the relay contact 27 closes a circuit which will supply the necessary current to maintain the relay R-1 energized for a predetermined period of time, for reasons which will be explained below. The circuit just referred to includes the 115-volt bus 30, a conductor 37, a contact 38 and contact arm 39 of a timing relay T, a conductor 40, the relay contact 27, the winding 23, the conductor 43 and the grounded bus 22.

The timing relay T, the components of which are shown within the broken-line enclosure, is a Westinghouse type TK Universal Timing Relay and was selected for this particular embodiment. Other makes or types of relays performing similar functions may be used. The relay T includes a motor 46 attached to a shaft 70 and a pair of worm gears 73 and 74, for actuating a pair of rotatable members 75 and 76, having attached thereto, respectively, contact arms 39 and 61. The arms 39 and 61 are adjustable with respect to each other and a plurality of contacts 38, 69 and 62. Normally arm 39 is in closed position with respect to contact 38 and open with respect to contact 69. Arm 39 is adjusted so that a predetermined time elapses before it moves into contact with contact 69. The length of time required for arm 39 to move from one position to the other will be presently described and will be designated herein as the waiting time. The arm 61 is also adjustable and in this particular embodiment moves into contact position with contact 62 at a period appreciably later than the time set for contact of arm 39 with contact 69. The reason for this latter timing arrangement will also be explained below and will be designated herein as the probationary time. When motor 46 is energized, as will be presently explained, contact arm 39, when moved to contact 69 position, will remain in said position until motor 46 becomes deenergized. The same applies to contact arm 61 with respect to contact 62. Said contact arms are pulled back to normal, when motor 46 becomes deenergized, by a pair of springs (not shown), the pull of said springs being appreciably less than the pull of the energized motor 46. How the motor 46 becomes energized will be described below.

At the instant relay R-1 is energized, a relay contact 29, normally open, is brought into closed position by armature 25. The closing of the relay contact 29 causes the simultaneous completion of two circuits. First, the circuit for energizing motor 46 of relay T is completed from the 115-volt bus 30, through a conductor 45, to said motor 46, through a conductor 47, the relay contact 29, a conductor 48, and the grounded bus 22. Second, the circuit for energizing a relay R-3 has a winding 50 which when energized actuates an armature 52, and it, in turn, controls the position of a relay contact 55, normally open. The flow of current for energizing the relay R-3 is

from the 115-volt bus 30, a conductor 49, the winding 50, a conductor 51, the relay contact 29, the conductor 48, and the grounded bus 22. When the winding 50 is so energized, the relay R-3, through its armature 52, closes relay contact 55. The significance of this last-named arrangement will be presently explained.

Up to this point of the description, relays R-1, T, and R-3 are energized. Relay R-1 is maintained in an energized state for a period, called hereinbefore the waiting time period. During this period, the tube 17 remains deenergized for the reasons set forth above. The length of this period is determined by the amount of time required to properly cool off tube 17. Consequently, arm 39 is set so that a period of time elapses, sufficient to cool off tube 17, before arm 39 moves to contact position 69.

At the conclusion of the waiting time period, motor 46, through the medium of its driving shaft 70 and worm gear 73, rotates member 75 and its contact arm 39 to the position of contact 69. The aforesaid rotation of arm 39 opens the relay R-1 circuit and thereby deenergizes same. In addition to this last-named action, the deenergization of relay R-1 causes the relay contacts 26, 27 and 29 to assume their normal positions. A fourth relay contact 28, controlled by the actuation of the armature 25, said relay contact being open when the relay R-1 is energized, closes upon deenergization of said relay R-1. In the closed or normal position, relay contact 28 provides a path for the conduction of current from the 115-volt bus 30, through a conductor 68, through said relay contact 28, the conductor 40, the contact arm 39, the contact 69, a conductor 57, a winding 58 of a relay R-2, through a conductor 59 to the grounded bus 22. The current passing through said last-named circuit energizes relay R-2 and causes an armature 71, actuated by said relay, to close a relay contact 60 attached thereto. As a result, the closing of the relay contact 60 makes the energization of the relay R-2 independent of the first means used to energize said relay, namely, the current path provided when relay contact 28 of relay R-1 assumed its normal or closed position.

Furthermore, as arm 39 moves from its contact 38 position and the circuit conducting the energizing current to the relay R-1 is opened, the relay contact 26 falls in place, completing the circuit energizing the breaker B. When the breaker B again becomes energized, it actuates the armature 72 and closes the relay contacts 33 and 34 attached thereto. The relay contact 33 completes the current circuit of primary 11 and tube 17 again becomes operative.

Since the deenergization of the relay R-1 places its attendant relay contacts in their normal positions, the relay contact 29 will be normally open and the motor 46 circuit would ordinarily be interrupted. However, the energization of relay R-3, as explained above, is held by an alternate circuit which includes the 115-volt bus 30, the conductor 49, winding 50 of relay R-3, the relay contact 53 of a relay R-4, a conductor 54, the relay contact 55, a conductor 56, and the grounded bus 22. The relay contact 53 of the relay R-4 is normally closed and in this position maintains the motor energized by the flow of current from 115-volt bus 30, through the conductor 45, the motor 46, the conductor 47, the conductor 51, the relay contact 53, the conductor 54, the relay contact 55, the conductor 56, and the grounded bus 22.

So far the relays R-2, R-3, breaker B and timing relay T are maintained in an energized state. This state is maintained for a period, hereinbefore referred to as the probationary time period, appreciably longer than the waiting time. If the tube 17 operates normally through the entire probationary time period, at the conclusion thereof, the arm 61 will have moved into contact with the contact 62 thereby completing the circuit energizing the relay R-4. The flow of current through this last-named circuit is from the 115-volt bus 30, through a conductor 63, a winding 64 on the relay R-4, a conductor 65, the contact 62, the contact arm 61, a conductor 66, and the grounded bus 22. When the winding 64 becomes thus energized, it actuates armature 67 thereof and opens the relay contact 53 attached thereto.

The opening of the relay contact 53 interrupts simultaneously the flow of current to the winding 50 of the relay R-3 and the motor 46 of the relay T. When the motor 46 is thus deenergized, the contact arms 39 and 61 are snapped back to their normal positions by a spring member (not shown). As a result, all of the components, hereinbefore referred to, will assume the positions indicated in Fig. 1.

With all of the components in their normal positions, the tube 17 is again energized and the test, which may be, for example, a life-span test, is continued until the tube 17 fails. It will be presently explained what takes place when this event occurs.

Thus far, the description of the circuit and its activities cover the situation in which the tube 17, at the onset, fails or backfires, and, as a result of such an event, is deenergized. Then there is the waiting period during which the tube 17 cools off and subsequently the probationary period during which tube 17 is again energized. There will now be described a condition when the tube 17 backfires during the probationary period.

Let it be assumed that tube 17 has passed the waiting period and is now operating during the probationary period. However, during the probationary period assume also that tube 17 fails, and, as a result, said tube draws an excessive amount of current. The relay R-1, which was deenergized at the conclusion of the waiting period, becomes again energized and is so energized during the period that relay T, breaker B, relays R-2 and R-3 are also energized.

As a result of relay R-1 being energized during the probationary period, relay contact 26 of relay R-1 opens and relay or breaker B becomes deenergized. Subsequently relay contacts 33 and 34 open their respective circuits, causing power supply 10 to be interrupted and thus again deenergizing tube 17 and operating the counter 35. Relay contact 27 now closes the circuit which supplies current to the winding 23 of the relay R-1 in the manner hereinbefore described and maintains the relay R-1 energized when current ceases to flow in tube 17.

Attention is called to the fact that the contact arm 39 of relay T is in the contact 69 position during the probationary period and, as pointed out hereinbefore, maintains this position until the motor 46 of relay T is deenergized. Therefore, the contact arm 39 keeps the particular circuit, connected therewith, energized and said circuit, in turn, maintains a flow of current through the winding 58 of relay R-2. Relay R-2 when energized maintains the relay contact 60 closed, and by said last-named means completes the cir-

cuit supplying current to energize the relays R-1 and R-2.

Also, as a result of relay R-1 again becoming energized, the switch 29 is drawn into closed position to complete the current supply circuit of motor 46. At the same time the relay R-3, which has been energized as described hereinbefore, provides a parallel current supply circuit to motor 46. However, as contact arm 61 continues to rotate, it will come into contact position with contact 62 thereby completing the circuit energizing relay R-4 as described earlier. When this occurs, the relay R-4 actuates its armature 67 which, in turn, opens the normally closed relay contact 53. Under normal conditions, when tube 17 operates properly during the probationary period, the opening of the relay contact 53 would open the motor 46 circuit and the entire circuit would return to normal as previously recited. However, despite the opening of the relay contact 53 of relay R-4, the motor 46 circuit remains operative because the relay contact 29 is in closed position and maintains a flow of current to said motor.

The ultimate result of the second short or overload occurrence in tube 17 is to lock in the entire circuit and maintain the test circuit inoperative until the tube 17 is removed. Upon removal of tube 17, switch 21, which may be a momentary-break type, is opened. This results in deenergization of the motor 46 and a return to normal position of the contact arms 39 and 61. The return to normal position of the contact arms 39 and 61 of the timing relay T causes all of the relay contacts controlled by the relays R-1, R-2, R-3, R-4 and breaker B to return to their normal positions as indicated on the drawing in Fig. 1.

Actually, although the above events were described as series or sequential occurrences, the events take place substantially instantaneously. Furthermore, should the tube 17 operate normally but fail at the expiration of its life span, the same events just described would transpire, except that the probationary time period would be eliminated as the recurrence of the tube failure would commence immediately after the conclusion of the waiting time period.

Although not indicated on the drawing, because it is obvious to those versed in the art, means may be provided for determining the amount of time elapsed between each successive breakdown or between the reenergization of tube 17 during the probationary period and its final demise.

Figs. 2 and 3 are graphs which illustrate the relation of operation of the various relays with respect to time. In Fig. 2 the graph shows the relation of various components with respect to time when the tube 17 under test backfires after it has been put into operation for the first time. This backfire occurs with reference to time at point A of aforesaid graph and, as pointed out hereinbefore, relay R-1 is energized and remains so for the period between points A and B, designated hereinbefore as the waiting period. It will be seen from the graph that the power for the period between points A and B has been interrupted. At the time relay R-1 becomes energized, relays T and R-3 also become energized as indicated in the graph and are active for said period of time between A and B. At the end of the waiting period or reference B, R-2 becomes energized, while relays T and R-3 are still energized. The aforesaid relays are maintained in an energized state for the period between points

B and C designated hereinbefore as the probationary time. It should be noted that between points B and C relay R-1 is inactive, and in its normal position permits the power supply to become active as shown on the graph between points B and C. At the end of the period between points B and C, R-4 becomes energized as described above and all of the other relays are deenergized and returned to their normal positions. Beyond point C if the tube behaves normally, the relays will remain deenergized and the life test to which tube 17 is being subjected will continue until the tube deteriorates. When this point is reached, the relays will again become energized and go through the two cycles above described.

In Fig. 3, the chart indicates a condition in which the tube 17 backfires during the probationary period B to C. When this backfire occurs relay R-1 will be energized at the instant the backfire in tube 17 occurs and the power interrupted as indicated on said graph. During the period between B and C relay R-2 being energized will cause relays T and R-3 to become locked in and power will remain interrupted until the necessary steps hereinbefore described have been taken.

It will be readily seen from the foregoing description of the invention that there is provided an automatic device which, when once set into operation, will perform the duties of a human observer and thereby permit the continuous test of a device under observation during periods of time when human attendance would entail an unnecessary expense. A further feature of the device of the present invention is the elimination of possible fire hazards which are present when a device under test causes an overload of a test circuit in the absence of a human observer.

The particular embodiment of the present invention which has been illustrated and described was selected for the purpose of setting forth the principles involved. It will be obvious that the invention may be modified to meet various conditions which may arise in different specific uses and it is, therefore, intended to cover by the appended claims all such modifications which fall within the true spirit and scope of the present invention.

What is claimed is:

1. In combination with an electric current-operated test circuit, means for interrupting the flow of current in said test circuit when said flow of current exceeds a predetermined value, said interrupting means including a first normally energized solenoid-operated switch having a pair of normally closed contacts in said test circuit for controlling the flow of current in said test circuit, a second solenoid-operated switch having a first pair of contacts connected in the circuit with the solenoid of said first-named switch and a power source for controlling the flow of current through the solenoid of said first-named switch, means for connecting the solenoid of said second-named switch to said test circuit, whereby upon the occurrence of said excess flow of current in said test circuit, said second-named switch, in response to said current, causes said first-named switch to interrupt the flow of current in said test circuit, timing means energized by a second pair of contacts on said second switch for maintaining said interrupting means in operation for a predetermined period of time and for restoring the flow of current in said test circuit at the

expiration of said last-named period for another predetermined period of time, and holding means for maintaining said interrupting means operative if said second solenoid-operated switch is again energized by the occurrence of excess current in said test circuit during said last-mentioned predetermined time, said holding means being deenergized by removal of said cause of excessive current flow.

2. In combination with an electric current-operated test circuit, means for interrupting the flow of current in said test circuit when said flow of current exceeds a predetermined value, means for maintaining said interrupting means in operation for a predetermined period of time, means for restoring the flow of current in said test circuit at the expiration of said last-named period, said restoring means including a normally energized solenoid-operated relay having a contact for controlling the flow of current in said test circuit, a second relay having a contact electrically connected to the solenoid of said first-named relay for controlling the flow of current through said solenoid, a timing switch connected to the solenoid of said second-named relay for controlling the flow of current through the solenoid of said second-named relay, means for energizing said timing switch, whereby upon the expiration of said last-named period said timing switch causes said second-named relay to operate said first-named relay to restore the flow of current in said test circuit for another predetermined period of time, and holding means for maintaining said interrupting means operative if said first-named means again interrupts the flow of current in said test circuit during said-mentioned predetermined time, said holding means being deenergized by removal of said cause of excessive current flow.

3. In combination with an electric current-operated test circuit, means for interrupting the flow of current in said test circuit when said flow of current exceeds a predetermined value, means for maintaining said interrupting means in operation for a predetermined period of time, means for restoring the flow of current in said test circuit at the expiration of said last-named period, said restoring means including a normally energized solenoid-operated relay having a pair of contacts presently open in said test circuit for controlling the flow of current in said test circuit, a second solenoid-operated relay, a first pair of contacts of said second relay being presently open and connected to the solenoid of said first-named relay and a power source for controlling the flow of current therethrough, a second pair of contacts of said second relay being presently closed and connected to the solenoid of said second-named relay to control the flow of current through said last-named solenoid, a motor-operated timing switch having a pair of contacts presently closed and connected in said circuit with the second pair of contacts of said second relay to further control the flow of current in the solenoid of said second relay, whereby upon the expiration of said last-named period, said timing switch opens its previously-mentioned contacts causing the contacts of said second relay to reverse their positions and thereby cause the contacts of said first relay to reverse their position and restore the flow of current in said test circuit for another predetermined period of time, and holding means for maintaining said interrupting means operative upon said-named means again interrupting flow of current

in said test circuit during said last-mentioned predetermined time, said holding means being deenergized by removal of said cause of excessive current flow.

HANS KLEMPERER.
